EDGING MACHINE

Fred Ricks and John Hunter Andrews, Leicester, England, assignors to United Shoe Machinery Corporation, Paterson, N. J., a corporation of New Jersey

Application June 1, 1936, Serial No. 82,729
In Great Britain July 5, 1935

5 Claims. (Cl. 69—1)

This invention relates to edging machines and is illustratively described as embodied in a machine of the type shown in Letters Patent of the United States No. 1,464,504, granted August 14, 5 1923 on an application of Joseph Fossa.

Such machines commonly employ a U-shaped searing tool which is applied to the margin of a piece of work, such as a portion of the uppor of the shoe, to shrink the margin of the leather 10 and cause it to curl so that in the finished piece, the edge presents only the grain surface instead of the flesh surface which resulted when the piece was originally cut out of the skin. The tools of such machines are sometimes heated by means of 15 an oxyacetylene torch and at other times by the passage of an electric current through the tool. Difficulty has been experienced particularly in machines of the latter type in clamping the legs of said tools to the electric leads through which 20 current is supplied thereto. It will be understood that the gripping of the tool to the lead must be effective not only to prevent arcing between the two parts but, furthermore, must insure the passage of the full current through the tool 25 without that resistance which would result from a poor contact between the clamping member and the tool. An object of the invention is to provide improved clamping mechanism for machines of this general type. In accordance with features of 30 the invention, the mechanism is arranged to provide for several turns of the clamping member after it has been brought into full engagement with the tool, thereby to displace any foreign matter. As illustrated herein, the clamping 35 member is spring pressed into engagement with the leg of the tool and provision is made for turning that member by a screw having a tongue-and-groove connection thereto. The arrangement allows two complete turns of the screw to be made 40 before the two parts of the clamping member are brought into positive engagement with one another and, hence, with the tool.

These and other features of the invention will 45 be more fully understood from the following description, taken in connection with the accompanying drawing, in which

Fig. 1 is a side elevation of one of the electrical leads of such a machine and showing one leg of 50 the tool held in position therein by our novel clamping mechanism;

Fig. 2 shows the two-part clamping member removed from the lead;

Fig. 3 is a fragmentary view of the tongue-and-55 groove connection between the parts of said

clamping member, taken at right angles to Fig. 2, and

Fig. 4 shows, on an enlarged scale, a U-shaped searing tool suitable for use with this clamping mechanism.

A lead 10 to which electric current is supplied through a horizontal extension 12 is arranged to be vertically positioned in the machine and is provided with a recess in the form of a transverse slot 14 near its lower end to receive the horizontally out-turned portion 16 of the leg 18 of a U-shaped searing tool T, such as is shown in Fig. 4. This tool has a substantially horizontal work-contacting portion 20 and its other leg 22 is turned outwardly at 24 in the opposite direction. It will be understood that a machine of the type shown in the Fossa Patent No. 1,464,504, mentioned above is provided with two such leads 10, each receiving one of the out-turned ends 16 or 24 of the tool T. The body 10 of the lead is provided with a bore 26 which is enlarged at 28 to receive a two-part clamping member C. The lower part 29 of this clamping member comprises a rod 30 having a sliding fit in the bore 26 and the lower end of this rod is adapted to contact with and clamp the out-turned leg 16 of the tool in the slot 14. The upper part 32 of the clamping member has a portion 34 threaded for engagement in the bore 28. The lower end of this upper part 32 is provided with a slot or groove 36 to receive a tongue 38 on the lower part 29. These parts are held together by a pin 40 which passes through a slot 42 in the tongue 38. A spring 44 surrounding the adjacent ends of the two-part clamping member bears against a shoulder 46 on the lower part and a shoulder 48 adjacent to the threaded portion 34 on the upper part, this tending normally to hold these parts in extended position.

Assuming that the threaded portion 34 has been turned by means of a wrench applied to its head 50 thereby to draw back the clamping rod 30, the tool T is positioned with its out-turned portion 16 in the slot 14 of the lead. The clamping member is then turned to bring the lower end of the clamping rod 30 into contact with the tool. After contact has been established, the spring-pressed clamping rod 30 may be given approximately two full turns before the spring 44 is compressed sufficiently to allow the tongue 38 to seat in the groove 36 and thus force the clamping rod 30 into positive engagement with the tool.

By thus providing for several turns of the spring-pressed clamping member while it is in engagement with the tool, a full electrical con- 55

tact will be assured, even though there may be present in the slot 14 some accumulation of charred material, such as results from the treatment of the leather or from the corrosion of the parts due to the repeated heating and cooling of the tool. The scraping action of the lower clamping rod 30 on the tool will wear away any such corrosion and while assuring efficient electrical contact, will provide an arrangement in which 5 the tool may readily be removed and replaced. It will be noted that the threaded portion 34 of the clamping member is at a distance from the tool so that the heat transmitted thereto will be very much lessened.

10 15 Having thus described our invention, what we claim as new and desire to secure by Letters Patent of the United States is:

1. A machine for finishing the edge of a piece of leather comprising, in combination, a substantially U-shaped tool having legs, supports recessed to receive said legs, one of said supports being provided with a spring-pressed clamping member, and means to rotate said clamping member to move it into clamping position.
2. A machine for finishing the edge of a piece of leather comprising, in combination, a substantially U-shaped tool having legs, supports recessed to receive said legs, one of said supports being provided with a spring-pressed clamping member, and means to bring said clamping member into clamping position constructed and arranged to impart several turns to said member after it has been brought into contact with the leg of the tool.
3. A machine for finishing the edge of a piece of leather comprising, in combination, a substantially U-shaped tool having legs, supports recessed

to receive said legs, one of said supports being provided with a spring-pressed clamping member, and means to bring said clamping member into clamping position constructed and arranged to impart several turns to said member after it has been brought into contact with the leg of the tool, said means also being arranged to bring the clamping member into positive engagement with the tool.

4. In a machine of the class described, a substantially U-shaped tool having legs and adapted to be heated by the passage of an electric current to treat the margin of a piece of leather, electric leads provided with recesses to receive the legs of said tool, one of said leads being provided with a clamping member having slidably interconnected parts constructed and arranged for rotation together, and a spring tending to separate said parts, one of said parts being adapted to contact with the leg of the iron to clamp it in position and the other part being threaded in said lead.

5. A machine for finishing the edge of a piece of leather comprising a substantially U-shaped shrinking tool having legs portions of which are turned outwardly, electric leads arranged in an upright position and provided with horizontal slots to receive the out-turned portions of the legs of the tool, one of said leads being hollow to receive a two-part clamping member, one part of which is arranged for engagement with the out-turned leg and the other part of which is threaded in the lead, a tongue-and-groove connection between said parts whereby they may be turned together, and a spring tending to separate said parts.
